Primary Examiner — Elizabeth J Oswecki(74) *Attorney, Agent, or Firm* — Honigman Miller Schwartz
and Cohn LLP(57) **CLAIM**

The ornamental design for a monetary device, as shown and described.

DESCRIPTION

FIG. 1 is a perspective view of a monetary device showing my new design;

FIG. 2 is a front view of the monetary device of FIG. 1;

FIG. 3 is a back view of the monetary device of FIG. 1;

FIG. 4 is a left view of the monetary device of FIG. 1;

FIG. 5 is a right view of the monetary device of FIG. 1;

FIG. 6 is a top view of the monetary device of FIG. 1; and,

FIG. 7 is a bottom view of the monetary device of FIG. 1.

The broken lines shown in the drawings represent portions of the monetary device that form no part of the claimed invention.
